UNITED STATES PATENT OFFICE

2,154,350

CONTAINER COVER APPLYING MACHINE

Frank O'Neill, Jr., New York, N. Y., and Albert F. Pityo, Clifton, N. J., assignors to Tamper-Proof Seal Corporation, New York, N. Y., a corporation of Maryland

Application October 27, 1933, Serial No. 695,520
Renewed April 8, 1938

29 Claims. (Cl. 226—81)

This invention relates to container cover applying machines, and has for its principal object to provide a machine for applying the container cover disclosed in the patent of Frank O'Neill, Jr., No. 1,828,906 issued October 27, 1931, according to the method also disclosed therein. The disclosure of that patent, therefore, is hereby incorporated into this application.

Other objects and features of novelty will be apparent as the following description proceeds, reference being had to the accompanying drawings, in which

Figure 1 is a vertical axial section through the head of the container cover applying machine according to the preferred embodiment of the present invention;

Figure 2 is a radial section through a container with a cover being applied thereto, taken along the line 2—2 of Figure 1;

Figure 3 is a portion of Figure 1, showing the starting position of the parts;

Figure 4 is a detail of the cam track pad for the paper spreading movement;

Figure 5 is a detail of the cam track pad for striking the roll flattening blow;

Figure 6 is a radial section taken along the line 6—6 of Figure 3;

Figure 7 is a plan of the crimping table, the folding mechanism and one-half of the cam plate being removed to show the crimping mechanism;

Figure 8 is a vertical section taken along the line 8—8 of Figure 7;

Figures 9, 10, 11 and 12 are detail plans showing the operation of the crimping mechanism;

Figure 9 shows the initial position;

Figure 10 shows the roll started;

Figure 11 shows the roll completed, and

Figure 12 shows the roll flattened.

Referring more specifically to the drawings the improved cap blank is shown in Figures 1, 2 and 3 as comprising a central body portion 1 adapted to overlie the mouth of a bottle or other container, radial, substantially T-shaped fingers 2, 3, 4 and 5 and intervening radial tabs 6, 7, 8 and 9. In applying the cap to a bottle the central body portion 1 is placed over the mouth of a bottle and in contact therewith. The tabs 6, 7, 8 and 9 are then bent downwardly over the bottle lip. Next the fingers 2, 3, 4 and 5 are bent downwardly over the bottle lip overlying the tabs 6, 7, 8 and 9. The adjacent lateral ends of the fingers 2—3, 3—4, 4—5, and 5—2 are then secured together in a manner hereinafter to be described, thereby causing the fingers to constitute a constricted band gripping the bottle neck below the

lip thereof, as shown in Fig. 1, to preclude removal of the cap without destruction thereof.

To facilitate feeding the cap blank into a position overlying the bottle mouth, each blank is preferably formed with one or more apertures which are successively entered by a suitable projection on the feeding mechanism of the bottle capping machine, not shown. This insures positive feeding of the cap-blank ribbon and the accurate positioning of each blank relative to the bottle upon which it is to be secured.

The cap blank is preferably made of paper and after certain printed matter has been applied thereto the blank is treated with a waterproof coating. The central body portion of the blank and selected ones or all of the tabs and fingers will, in use, usually be provided with suitable advertising matter.

This invention provides a new means for securing together complementary portions of the cap blank to cause the completed and applied cap tightly to be secured upon the bottle and to preclude removal of the cap without destruction thereof. To this end, the fingers 2, 3, 4 and 5 are provided, at their outer ends, with lateral extensions the combined length of which is greater than the circumference of the bottle neck. The adjacent ends of these extensions are adapted to be interlocked to form a continuous band about the bottle neck beneath the lip thereof. Preferably, but not necessarily, the lateral extensions of two of said fingers will be of soft metal or similar material which will retain any given shape. This may be accomplished by securing to the radial fingers 2 and 4 soft metal strips s. These strips are preferably attached to the fingers by tangs punched from said strips and projected through the fingers and turned back on the underside thereof. The strips s are longer than the width of the head of the fingers 2 and 4 and project beyond the sides of the heads as shown in Figs. 2 and 11.

The cap blanks preferably are fed into a suitable automatic capping machine in ribbon form the finger 5 of each blank being formed integral with the finger 3 of a succeeding blank. Upon arrival at capping position each blank is severed from the ribbon and attached to a bottle.

The container cover applying machine according to the present invention comprises generally an operating head, which can be used in either a line delivery machine or in a rotary machine, although in the drawings we have shown it as originally applied to a line delivery machine.

The frame of the head comprises generally an

upper cylindrical plunger barrel 10, and a lower flat curling table 12. Telescoping plungers 13, 14, 15, and 16 are slidably mounted in the barrel 10, and respectively carry folding fingers, or parts 5 cooperating therewith, for folding down the flaps or tabs of the container cover.

The curling table 12 has four radial guideways 17, 18, 19 and 20 in which are mounted slides carrying mechanism for crimping, or rolling up together, the metal clip and the paper strips which form the sealing band about the container neck. These slides are operated by rollers following in cam tracks in a cam plate 21 rotatably mounted above the curling table 12, and driven by a gear 15 22 meshing with a pinion 23 keyed on the shaft of wheel 24 driven by a worm 25 from the source of power for the machine.

The machine therefore comprises broadly a folding finger mechanism and a curling mechanism. The folding finger mechanism positions the blank and folds it to bring the parts into position to be operated upon by the curling mechanism, and hold them in that position. The curling mechanism cooperates with the folding finger mechanism to complete the operation, by rolling the metal and paper ends together to form the constricted band about the container neck.

Folding finger mechanism

30 The cover clamping plunger 13 comprises a flat head, and a stem slidable in a bore in the diagonal finger plunger 14, being urged outwardly by a coil compression spring 26. This stem is retained by a pin 27 extending through the plunger 35 14, and working in a slot in the plunger 13.

The diagonal tab finger plunger 14 has a cupped head provided with four depending integral short fingers. The stem of this plunger is the longest, and it extends up out of the barrel 40 10, being made in two threaded parts for easy assembly. The upper part passes through the end of an operating lever 30.

45 The diameter flap finger plunger 15 has a generally flat head, slotted to pivotally receive four long fingers 32. These are spring pressed outwardly and the stem of this plunger is of intermediate length, and it is urged downwardly by a coil compression spring 33.

50 The head of the outer plunger 16 is cupped and radially flanged, this flange and the head of plunger 15 being held in alignment by a vertical pin 35 passing through both. This flange is cushioned by coil compression spring 36 in recess in the bottom flange of the barrel 10. This flange cooperates with operating lugs 37 on the fingers 55 32.

Operation of folding finger mechanism

60 The flat paper caps with the metal clips performed thereon are supplied to the container cover applying machine by suitable feeding mechanism preferably comprising a reciprocating finger on a slide, the individual blanks being severed from a roll or strip after the initial feeding movement. The container or bottle as shown 65 by the dotted lines, is in the position shown in Figure 3, with a container cover blank in position thereabove as shown by the dotted lines, having been located by the feeding mechanism just referred to. The usual bottle elevating mechanism now raises the bottle, which raises the plunger 13 with the blank therebetween, against the action of the spring 26. This movement brings the cover blank against the four short fingers on the head of the plunger 14, which fold 70 75 down the short diagonal tabs of the cover blank.

Further upward movement of the bottle or container causes the head of plunger 13 to engage the head of plunger 14, so that the two move bodily upward as a unit. This movement causes the diameter flap folding fingers 32 to engage 5 the diameter tabs and fold the diameter tabs downward.

Further upward movement of the bottle causes the head of plunger 14 to abut the head of plunger 15 and the three now move upward as 10 a unit. When the operating lugs 37 engage the flange of plunger 16, the fingers 32 are cammed inwardly thereby, to bring the diameter tabs into snug engagement with the neck of the bottle.

Curling mechanism

15

Mounted in the guide 17 of the curling table 12 as shown in Figure 7, is a slide 40 which carries the mechanism for engaging the metal clips S, conforming the central portion thereof to the 20 container neck, and rolling up the preformed ends S' thereof. An identical slide is mounted in the opposite guide 19, with identical mechanism for performing the same operations on the other side of the container neck.

25 The slide 40 has heels 70 which abut the guide 17 to limit the total inward movement of this slide 40. A wide central longitudinal groove is formed in the upper side of the slide 40, and this groove is flared at its inner end, so as to receive a Y-plate 41. The Y-plate 41 is normally retracted to hold its fork against the flared end of the groove in the slide 40, by coil compression springs 42 which are interposed between abutments on the slide 40 and the heel of the Y-plate 30 41.

35 Deeper angularly disposed grooves are also formed in the inner end portion of the slide 40, and slidably receive curling bars 44, which are notched or halved together in crossing relation, 40 with clearances for simultaneous movement. The rear ends of these curling bars 44 are also notched to respectively receive the branches or forks of the Y-plate 41.

45 Pivoted on the under side of the slide 40, are a pair of clip locating fingers 45. These fingers 45 are notched or halved together in crossing relation. The front ends of these fingers are of thickness sufficient to bring their tops flush with the bars 44 and the Y-plate 41. Springs 47 50 mounted in bores in the slide 40, respectively urge the fingers 45 into their position shown in Figure 7.

55 The Y-plate 41 carries a roller 48 which follows in an intermediate cam track 49 in the cam disk 21.

60 Displaced 90 degrees from the guide 17 is the guide 18 in which is mounted a slide 52, which carries the mechanism for conforming the central portion of the paper strip to the neck of the 60 container, and for coordinating the ends t thereof with the ends S' of the metal clip. An identical slide is mounted in the opposite guide 20, with identical mechanism for performing the same operations on the other side of the container 65 neck.

65 The slide 52 has shoulders 71 operating in recesses in the guide 18, which abut the inner ends of the recesses to limit the inward movement of the slide 52. A Y-plate 53 is slidably mounted in 70 a central groove in the slide 52, the inner end of the groove being flared to receive the fork thereof. The front end of the slide 52 has deep crossed grooves therein, in which are slidably mounted paper spreading bars 54. These bars 75

are notched or halved together with clearance for simultaneous movement tangential to the container neck. Spring pressed rods 55 enter bores in the butts of these bars 54 and urge them 5 tangentially toward the container.

The Y-plate 53 carries a roller 56 which follows an outer track 57 in the cam plate 21. As shown in Figure 4, this track has a spring pressed pad 67 at a predetermined point therealong, for 10 a purpose which will hereinafter appear.

The slide 52 carries a roller 60, which follows an inner track 62 in the same cam plate 21. As shown in Figure 5, a spring pressed pad 66 is mounted at a predetermined point along the 15 track 62, for a purpose hereinafter described.

Operation of curling mechanism

After the container cover blank has been folded down as described in the operation of the 20 finger folding mechanism, the curling mechanism operates to coordinate the metal clip and the paper strip and roll them up together. The cover is already on top of the container mouth, and is held by the long folding fingers 32, which 25 hold the diameter flaps against the neck of the container.

The power of the machine is applied to the worm 25, which through the gearing 24, 23 and 30 22, drives the cam plate 21. The track 49 cams the roller 48 inward, causing the Y-plate 41 and the slide 40 to move inward bodily as a unit. This causes the clip locating fingers 45 to engage the metal clip and form it to the container neck. In this operation the fingers 45 spread 35 until they snugly enter the preformed angle of the metal clip, as shown in Figure 9.

The track 62 now causes the roller 60 to move the slide 52 inward, causing the concave face 59 at the inner end of the slide 52, to engage the 40 paper strip, and conform the same snugly to the neck of the container. Then the spring pressed pad 67 in track 57 cams the roller 56 inwardly, forcing the Y-plate 53 to slide inwardly on the slide 52. This movement of the Y-plate, by the 45 forks thereof engaging notches in the crossing fingers 54, cams these fingers 54 tangentially with respect to the container neck until the ends of fingers 54 abut the ends of fingers 44, as shown in Figure 10. The spring mounting of the pad 67 cushions this movement. By this movement of the fingers 54, the ends *t* of the paper strip are 50 wiped against the turned back ends *S'* of the metal clip, which are being held by the clip spreading fingers 45. This brings the parts to the position shown in Figure 10.

The next step involves further action with respect to the slide 40.

The track 49 cams the roller 48 further inwardly, causing the Y-plate 41 to move inward with respect to the slide 40, which is at the limit of its inward movement, because the heels thereof engage the outer end of the guide 17.

This further inward movement of the Y-plate 41 causes the forks thereof to cam the curling bars 44 tangentially to the container neck. In this movement, the bars 44 slide along the adjacent faces of the clip holding fingers 45.

The curling bars 44 have curling dies 65 in the inner ends thereof, constituted by concave 70 recesses or cylindrical depressions. Hence the forward movement of the bars 44 cause the dies 65 to engage the preformed (curl) ends *r* and start to roll them up, as shown in Figure 10.

It should be noted that during the tangential 75 movement of the dies 65, the ends of the bars

44 abut the ends of the bars 54. As to the bars 44 are positively driven (roller 48) and the bars 54 are merely resiliently pressed (spring plungers 55) the ends of bars 54 exert a back pressure which is overcome, but always maintains pressure 5 between the ends of fingers 54 and 44.

As the bars 44 slide along the fingers 45, the paper strip *t* which is held onto the metal strip end *S'*, is rolled up therewith, as shown in Figure 11, forming the roll *x*. 10

The track 62 now cams the roller 60 outward, which moves the plate 52 back bodily a distance slightly larger than the diameter of roll *x*. As the spring plungers 55 are bearing on the bars 54, the abutment with the fingers 44 is maintained, 15 but the fingers are out of alignment a distance greater than the diameter of the roll *x*.

The track 49 now cams the roller 48, to move the Y-plate 41 outward, which results in retracting the bars 44 for a distance sufficient to 20 permit the spring plungers 55 to project the fingers 54 to a position over and beyond the rolls *x*, as shown in Figure 12.

The track 62 contains a spring pressed pad 66, which strikes the roller 60, and drives 25 it inward, carrying the slide 52 and the bars 54 therein as a unit. Thus a sort of hammer blow is given to the bars 54 overlapping the rolls *x*, which flattens these rolls as shown in Figure 12. The spring mounting of the pad 66 allows for 30 variation in the size of containers, and avoids breakage of bottles. The surface of the bars 54 at the points of contact with the roll *x* may be depressed, or engraved, so as to give any desired shape to the flattened roll, or to impress 35 a character or seal thereon.

Of course, as the mechanisms in the guides 19 and 20 are respectively identical with those in the opposite guides 17 and 18, and as the cam tracks 49, 57 and 62 are continued and repeated 40 for the other half of the cam plate, the operations just described are duplicated simultaneously on the other side of the container neck.

It should be noted that a ninety degree movement of the cam plate 21 completes the opera- 45 tion, and the next ninety degree movement is employed for return movement, so that a complete cycle of operations takes place in a 180 degree movement of the cam plate. Hence two successive covers can be applied by one revolution 50 of the cam plate 21.

While the drawings show the curling or crimping or sealing members as sliding on the curling table, it is to be understood that these curling members may be otherwise mounted, so as to 55 otherwise move in for their functions, instead of sliding in, as shown. The movements in this event are cam actuated by the vertical movement of the bottle, thus eliminating the power 60 drive 24, 25, etc. Furthermore, these modifications may be designed to permit a more compact head, allowing the heads to be more closely spaced as is desirable with a rotary type of bottle conveying mechanism. 65

Our invention embraces such embodiments of the broad idea as fall within the scope of the appended claims.

We claim:

1. In a container cover applying machine, in 70 combination, means for folding portions of a container cover blank down around the neck of the container, means for placing portions of said blank in overlapping contact and means for rolling said overlapped portions together spirally, 75

- to form a permanent union between said portions.
2. In a container cover applying machine, in combination, means for folding portions of a container cover blank down around the neck of the container, means for placing portions of said blank in overlapping contact, means for rolling said overlapped portions together spirally, and means for compressing a portion of the roll, to 5 form a permanent union between said portions.
3. In a container cover applying machine adapted to apply a cover to a container, in combination, telescoping plungers carrying fingers for folding portions of said blank down around the 10 neck of the container, means for placing portions of said blank in overlapping contact, and means for rolling said overlapped portions together spirally, to form a permanent union between said portions.
4. In a container cover applying machine, in combination, means for folding portions of a container cover blank down around the neck of the container; a curling table, and mechanism thereon comprising means for placing portions of said 15 blank in overlapping contact, and means for rolling said overlapped portions together spirally to form a union between said portions.
5. In a container cover applying machine adapted to form from a blank a band about the 20 container neck, the combination of means for placing portions of said blank in contacting relation, and means for rolling said contacting portions together.
6. In a container cover applying machine 25 adapted to form from a blank a skirt and a band about the container neck, the combination of means for placing portions of said blank having band forming portions, means for placing said portions in overlapping relation, and means for rolling said overlapped portions together.
7. In a container cover applying machine 30 adapted to form from a blank a band about the container neck, the combination of means for urging a first end portion of said blank toward said container neck, means for urging a second end portion of said blank toward said container neck and wiping it into overlapping relation with the first, and means for rolling said overlapped portions together.
8. In a container cover applying machine 35 adapted to form from a blank a band about the container neck, the combination of means for placing portions of said blank in overlapping relation, a curling die, and means for moving said die to engage the ends of said overlapped portions and roll them together.
9. In a container cover applying machine 40 adapted to form from a blank a band about the container neck, the combination of a finger, means for urging said finger toward said container neck to apply a first end portion of said blank thereto, means for applying a second end portion in overlapping relation with the first, and means for rolling said overlapped portions together.
10. In a container cover applying machine 45 adapted to form from a blank a band about the container neck, the combination of a locating finger, means for urging said finger toward said container neck to apply a first end portion of said blank thereto, a wiper bar, means for urging said bar toward said container neck to apply a second end portion thereto and for moving said bar along said finger to wipe said second end portion into overlapping relation with the first, a 50 curling die, means for moving said curling die along said locating finger into engagement with the ends of said overlapped portions and with said wiper bar to roll said overlapped portions into a spiral roll. 5
11. In a container cover applying machine, in combination, means for holding a blank on the top of a container, means for folding down parts of said blank, means for folding down parts therebetween in overlapping relation therewith, 55 said second folded down parts having lateral extensions, and means for uniting said lateral extensions by their own materials to form a band about the container neck.
12. In a container cover applying machine, in combination, coaxial members relatively movable along their common axis, one of said members constituting a holder for a blank on the top of the container, and another of said members having fingers depending below said holder for folding down portions of said blank and means for uniting said portions by their own materials. 60
13. In a container cover applying machine, in combination, coaxial members relatively movable along their common axis, one of said members constituting a holder for a blank on top of the container, another of said members having pivoted depending fingers for folding down portions of said blank, means for moving said pivoted fingers inwardly to hold said folded down portions against said container neck and means for rolling said portions together. 65
14. In a machine for applying a cover to a container, in combination, means for holding a cover blank over the mouth of a container, means for deflecting outer portions of said blank downwardly and inwardly into contact with a reduced portion of said container below the mouth thereof, means for rolling together spirally adjacent portions of said blank, to unite the same and simultaneously constrict the periphery of said blank into gripping contact with the reduced portion of said container. 70
15. In a machine for applying to a container a cover blank comprising a central body portion, a plurality of radial fingers, and a bendable fastener secured to at least one of said fingers, in combination, means for holding said blank over the mouth of a container, means for deflecting said fingers downwardly and inwardly into contact with a reduced portion of said container below the mouth thereof, means for causing parts of said fastener to engage parts carried by other fingers and to wind portions thereof into a spiral, to effect a union between said parts and thereby produce at the lower portion of the completed cap an unbroken band gripping said reduced portion of the container. 75
16. In a machine for joining together portions of a container cover blank having secured thereto strips of bendable material, the ends portions of said strips being folded back and the extremities of said turned back portions being initially partially curled, the combination of means for placing a portion of said cover blank in contact with a turned back portion of said bendable strip, and means for completing the curling of the turned back portion of said bendable strip and simultaneously winding these into said portions of said cover blanks, thereby producing a spirally wound roll having alternate layers of metal and cover material. 80
17. In a container cover applying machine, a frame adapted to centrally receive a container neck, oppositely disposed slides on said frame, 85

5 relatively sliding bars on each of said slides, and means actuated by a common source of power for projecting said bars toward said container neck for applying a container cover thereto, one opposed pair of said slides being adapted to conform skirt portions of a cover to said container neck, and another pair of said slides being adapted to interlock a metal fastener with said conformed skirt portions to secure the cover on the 10 container neck.

15 18. In a container cover applying machine, means for folding skirt portions of a cover blank down around the neck of a container, and means for forming about the container neck a constricted band comprising parts of said skirt portions held together by a metal fastener, said band forming means comprising fastener manipulating mechanism and means for supporting said mechanism, said mechanism comprising 20 a fastener forming die and parts cooperating therewith to partly form said fastener before it contacts with the container neck.

25 19. In a container cover applying machine, in combination, means for holding skirt portions of the container cover in overlapping relation, comprising opposite holders, and means for moving said holders inwardly substantially radially toward the container neck; means arranged alternately with said holders for forming a metal fastener securing said overlapped portions together, each of said alternate means comprising a carrier, a bar slideable on said carrier, a fastener forming die on said bar movable therewith toward the container neck; means movable relative to said carrier and engaging said bar for sliding the same toward the container neck; and means for moving said carrier toward the container at a different rate of speed from that of said bar, whereby said metal fastener is partly formed before it contacts with the container 40 neck.

45 20. In a container cover applying machine, in combination, means for holding skirt portions of the cover in overlapping relation, a carrier, guides on said carrier, bars slideable in said guides toward the said overlapped portions, dies on said bars adapted to form metal fastening devices for securing said overlapped portions into a constricted band about the container neck, and means movable relative to said carrier and engaging said bars for sliding the same.

50 21. In a container cover applying machine, in combination, means for holding skirt portions of the cover in overlapping relation, certain of said skirt portions carrying metal pieces, and means for forming said metal pieces and overlapped portions into a constricted band about the container neck, comprising a carrier, bars slideable on said carrier, means movable relative to said carrier and engaging said bars for sliding and extending the same, and means for moving said carrier with said bars extended thereon toward the container neck to cause said bars to curl together said parts of a cover into a band about 55 said neck.

60 22. In a container cover applying machine, in combination, means for folding down portions of a cover blank about the neck of the container, means for placing portions of the blank into overlapping contact, means for forming a metal fastener interlocking with portions of said cover blank to secure them together about the container neck, comprising cooperating elements including a metal bending die, and means for relatively moving said cooperating elements with re-

spect to the container neck at different rates of speed, whereby said metal fastener is at least partly formed before it contacts with the container neck.

75 23. In a container cover applying machine, a head adapted to centrally receive a container neck, oppositely disposed guides on said head, cooperating fastener forming elements mounted in said guides and including a metal bending die, and means for causing relative movement of said cooperating elements to cause a substantial part of the fastener forming to take place before said fastener engages the container neck, and means for causing further operation of said fastener forming means to complete the fastener.

10 15 24. In a container cover applying machine, a head adapted to centrally receive a container neck, means for folding portions of a container cover blank down around said container neck at diametrically opposed positions and for folding other portions of said blank down over the first-mentioned portions at diametrically opposed positions therebetween, relatively movable parts mounted in said head at diametrically opposed stations spaced about the container neck, said parts being adapted to cooperate to form a metal fastener for securing said cover about the container neck, one of said parts having a metal bending die, and means for actuating said parts to partly form said fastener before it contacts the container neck, and thereafter complete the formation of said fastener in engagement with portions of said cover which contact the container neck by flattening said fastener against the resistance of the container neck, the flattening parts being mounted at diametrically opposite positions with respect to the container neck whereby the flattening forces thereof act in opposite directions upon diametrically opposite sides of the container neck substantially in a straight line extending through the axis thereof.

20 25 30 35 40 45 50 55 25. In a machine for applying container covers having a central mouth covering portion and a surrounding skirt portion carrying seal forming material, means for applying said central portion over the mouth of a container, means for collapsing said skirt portion about the neck of said container, and means operating solely upon said skirt and said seal forming material carried thereby for forming thereof a constricted band about the container neck.

60 26. In a machine for applying container covers having a central mouth covering portion and a surrounding portion carrying seal forming material, means for applying said central portion over the mouth of a container, means for collapsing said skirt portion about the neck of said container, means for bringing said seal forming material into contact with other parts of said skirt to form a constricted band about the container neck, and means for pressing said contacting parts toward the container neck to perfect the sealing thereof.

65 70 75 27. In a machine for applying container covers having a central mouth covering portion and panels extending outwardly therefrom, certain of said panels carrying attachment forming material applied thereto adapted to cooperate with parts of other panels to secure them together, means for folding down said panels to form a skirt about the container neck, constructed and arranged to fold down the attachment forming material carrying panels subsequent to the folding down of certain of the other panels, means

- for manipulating said attachment forming material carrying part and said cooperating part to bring them into contacting relation, and means projected inwardly toward the container neck to exert pressure on said contacting parts to perfect the sealing thereof.
28. In a machine for applying container covers having a central mouth covering portion and panels extending outwardly therefrom, certain of said panels carrying material applied thereto adapted to cooperate with cover material parts of other panels to secure them together, folding mechanism adapted to receive the mouth and neck of said container, means for effecting relative endwise movement of the container with the cover thereover and said folding mechanism, said folding mechanism operating to fold said panels down about the container neck to form a skirt, means for manipulating said material carrying part and said cooperating panel part to bring them into contact, and means projected inwardly toward the container neck to exert pressure on

said contacting material and part to perfect the sealing thereof and form a constricted band about the container neck.

29. In a machine for applying container covers having a central mouth covering portion and a surrounding skirt portion, comprising panels, certain of said panels carrying material adapted to cooperate with other panels to secure them together, means for holding said central portion over the mouth of a container, folding mechanism adapted to receive the mouth and neck of said container, means for effecting relative endwise movement of the container with the cover thereover and said folding mechanism, means for manipulating said panels to bring said material of one panel into contact with said material of the other panel, and means projected inwardly toward the container neck to exert pressure on said contacting material and part to form a constricted band about the container neck.

FRANK O'NEILL, Jr.
ALBERT F. PITYO.
